UNITED STATES PATENT OFFICE

2,467,978

BUFFING, POLISHING, OR SANDING
MACHINEKingdon Kerr, Los Angeles, and Malte Swensson,
West Los Angeles, Calif.

Application October 18, 1945, Serial No. 623,072

1 Claim. (Cl. 51—137)

1

Our invention relates to a buffing, polishing or sanding machine, and an important object of the invention is to provide such a machine that will replace manual sanding and polishing with substantially production line methods.

Another object of the invention is to provide a universally adjustable sanding and polishing mechanism, whereby the sanding and polishing may be conducted in a wide variety of angles.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of an embodiment of the foregoing objects.

Fig. 2 is a side elevational view of the same with the feeding mechanism omitted.

Fig. 3 is a section taken on the line 3—3 of Fig. 1.

Fig. 4 is an enlarged section, taken on the line 4—4 of Fig. 2.

Fig. 5 is a side elevational view looking in the opposite direction from Fig. 2, the feeding mechanism shown in Figs. 1 and 2 being omitted.

Fig. 6 is an elevational view of the feeding mechanism and also of associated parts in the aforementioned views.

Fig. 7 is a plan view taken on the line 7—7 of Fig. 6.

Fig. 8 is a transverse section taken on the line 8—8 of Fig. 7.

Fig. 9 is an enlarged cross-section taken on the line 9—9 of Fig. 2.

Fig. 10 is an enlarged, longitudinal section of a detail hereafter more fully described.

Fig. 11 is an enlarged section taken on the line 11—11 of Fig. 3.

Referring more in detail to the drawings, the reference number 10 indicates a base upon which the machine is supported. A suitable plate 12

2

is arranged under the base with a tapped opening for receiving a threaded, elevating stud 13. A hollow column 14 is mounted in the base 10 to swing therein about the longitudinal axis of the column and to move in a vertical plane. The stud 13 extends longitudinally through the column. A crank 15 is arranged on the upper end of the stud to manipulate same. A collar 9 is pinned or otherwise suitably fastened on the elevating screw 10. 13. A sleeve 16 fixed in the column 14 is engaged at one end by the collar 9 and at the other end by the crank 15. Thus when the screw 13 is rotated and thereby caused to move upwardly in Figs. 3 and 11, the collar 9 lifts the sleeve 16 and the therewith connected column 14. The column slides vertically in the base 10 and carries with it the present machine.

When rotated the other way, the stud 13 is drawn downward by reason of its threaded connection with the tapped plate 12.

Collars 17 and 18 are clamped upon the column 14 by any suitable arrangement. The means shown in the drawings, and specifically in Fig. 9, comprises a bolt 19 with an enlarged tapering end 20. The end 20 is threaded and screwed into a correspondingly tapped opening 21 in the collar.

Each of the bolts 19 has a tapering cam face 22 which bears against the column 14 when moved in that direction, to clamp the column against movement relative to the collar. Handles 23 are mounted on the bolts 19 for manipulation thereof. Turning either handle 23 in one direction, clamps the column in the manner described, and turning the handle in the opposite direction screws the cam face 22 away from the column, thus releasing same for movement relative to the collar.

Torque-resisting links 24 and 25 are respectively pivotally connected with the collars 17 and 18, and are pivotally connected with each other, as indicated at 26. The lower collar 18 is bolted or otherwise fixed upon the base 10, whereas the collar 17, when released by turning its handle 23, is freely slidable upon the column 14. To raise and lower the present machine, it is only necessary to loosen the bolt 19 in the collar 18. The torque links 24 and 25 prevent turning movement of the machine during the raising and lowering of same. To turn the machine about the vertical axis of the column 14, the bolts 19 in both of the collars 17 and 18 must be released. After the adjustment of the position of the machine, the bolts

19 are again tightened, to hold the machine in its desired operative position for buffing, sanding or polishing.

A horizontal arm 21 mounted on the column 14 carries a tubular cross member 28. Telescoped within the cross member 28 is a cylindrical pivot member 29. Plates 30 and 31 are respectively fastened upon the cross member 28 and upon the pivot member 29. The plate 30 contains a slot 32 with which a bolt 33 in the plate 31 cooperates. By this means the pivot member 29 may be turned about its longitudinal axis and held in adjusted positions by tightening the bolt 33.

The side plate 34 is supported on the pivot member 29 by lugs 35 and 36. Thus when the pivot member 29 is adjusted, the present machine is swung around the longitudinal axis of the pivot member 29. A motor 37 is in turn mounted on the side plate 34, through the intermediary of a vertical supporting bracket 38.

A side plate 40 is arranged opposite the side 34. These side plates are integrally connected by a preferably stainless steel plate 41. It is believed clear without further illustration that a hardwood table may be employed to back the top stretch of the endless belt 69. Rotatably mounted between the side plates are relatively large and small rollers 42 and 43 respectively, at opposite ends of the frame defined by the side and top plates. The shaft 44 of the large roller 42 is disposed in slots 45 in the side plates for adjustment. The motor 37 drives the large roller 42 through the intermediary of pulley 46 on the motor shaft, a pulley 47 on the roller 42 and a belt 48 that engages the pulleys.

Bolts 49 and 51 hold the lugs 35 and 36 on the frame and extend transversely therethrough. These bolts carry two nuts 50 and 52 on the outer ends thereof, for frame strengthening purposes and to hold the lugs 35 and 36 firmly on plate 34. The bolts 49 and 51 also extend through the member 29 to prevent turning thereof in lugs 35 and 36.

The shaft 53 not only rotatably supports the small roller 43 but also pivotally mounts side plates 54 and 55 upon the frame. A cross bar 56 connects the plates 54 and 55, while a bar 57 connects the side plates 34 and 40. The bar 56 has a tapped, transverse opening through which an adjusting screw 58 is helically turned. A collar 59 on one side of the bar 57 and a cotter pin 60 on the other side of the bar prevents the screw 58 from moving longitudinally through a smooth opening in the bar 57. Thus, by turning the screw 58, the bar 56 and thereby the plates 54 and 55, swing in one direction or another around the shaft 53, depending upon which way the screw is turned. A knob 63 is arranged to manipulate the screw 58. A medium-sized roller 61 is pivotally mounted on the plates 54 and 55 to be swung therewith upward toward, or downward away from, the frame of the machine. A wood block 62 connects the plates 54 and 55 at the end of the machine. Screws 63 hold the wood block and the side plates 54 and 55 together to cause said plates and the wood block 62 to move as a unit. A work shelf 64 is supported on arms 65 that are in turn held in adjusted positions on the plates 54 and 55 by bolt means 66 that engage in slots 67 on heads 68. An endless belt 69 of either felt or fabric material is arranged to travel around the rollers 42, 43 and 61, for buffing, sanding or polishing articles or materials.

Suitable feeding means, such as shown in Fig. 6, may be employed for feeding the work mate-

rial or the articles to be worked upon. Said means comprises an endless belt 70 that travels in the direction of the arrow B of Fig. 6, around driven and idler rolls 71 and 72, respectively. A motor 73 drives a belt 74, which in turn drives the roller 71. The belt 70 is arranged to travel along a suitable flat support or table 75 mounted on a frame 76. Abutments 77 on the belt 70 engage and advance frames 78 of any desired form for holding the work or articles to be sanded, buffed or polished. The frame 78 is illustrated in detail in Figs. 6 to 8.

Means for pressing the buffing or polishing belt 69 against the articles or work in the frame 78, includes a pad 79 pivotally depending from links 80 which in turn are pivotally connected with the frame of the machine. A brace member for the links comprises a turnbuckle arrangement 81 and a compression spring 82 that urges the turnbuckle outwardly from a shell enclosing said spring by bearing against a head 84 on a screw 85 of the turnbuckle. The brace device has a ball and socket connection 86 with the links 80. The spring 82 urges the pad 79 downwardly, within the endless belt 69, to cause the belt to firmly engage the articles or work being buffed, polished or sanded.

In the operation of our machine, articles to be buffed, polished or sanded are placed in the frame 78 and fed under the belt 69, in the manner shown in Fig. 6. The spring 82 depresses the pad 79 and thereby resiliently urges the buffing, polishing or sanding belt against the articles or work. Suitable adjustment may be made in connection with the spring 82 by means of the turnbuckle 81.

The entire machine may be raised or lowered by releasing the screw 19 in the lower collar 18 and then by turning the elevating crank 15. The links 24 and 25 will permit movements of the machine within a vertical plane, within the limits of the combined length of the links. If it is desired to turn the machine about a vertical axis, both collars 17 and 18 are first unloosened and are tightened again after the machine is manually swung to the desired position.

The belt 69 may be tightened by swinging the plates 54 and 55 downward, carrying the roller 61 with them. This adjustment is effected by turning the screw 58 by means of the knob 63. The bar 57 is the anchor bar, and the bar 56, with the plates 54 and 55, is adjusted relative to the relatively fixed bar 57. When removing the belt 69 for replacement or repair, the plates 54 and 55 are swung upwardly, so as to loosen the belt 69. The belt may then be slid off sidewise.

The bolt 33 locks the machine against swinging about a horizontal axis. Upon releasing the bolt 33, the machine can be swung about the axis of the pivotal member 29. The bolt 33 may then be tightened to hold the machine in such position. Buffed, sanded or polished articles or material may be placed on the shelf when the operation thereon is complete. The swinging adjustments of the machine about vertical and horizontal axes are relative to the frame 76 for the feeding belt 70.

It is believed clear from the drawings that the rollers 42, 43 and 61 are of different diameters. This provides means for sanding, buffing or polishing concave articles of different radii, while still obtaining close wiping action with the concave faces of such articles.

While we have illustrated and described what we now regard as the preferred embodiment of

our invention, the construction is, of course, subject to modifications without departing from the spirit and scope of our invention. We, therefore, do not wish to restrict ourselves to the particular form of construction illustrated and described, but desire to avail ourselves of all modifications that may fall within the scope of the appended claim.

Having thus described our invention, what we claim and desire to secure by Letters Patent is:

In a machine of the character described, a base support structure, a column disposed perpendicularly to said structure, means extending axially through the column for moving the latter relatively to said structure, a collar fixed to said structure and releasably engaged with the column, a second collar releasably engaged on the column and spaced from the fixed collar, and articulated means connecting the collars against relative rotation, said latter means comprising a pair of pivotally connected links having pivotal connection with said collars.
